US00D842276S

(12) **United States Design Patent** (10) **Patent No.:** **US D842,276 S**
Brunner et al. (45) **Date of Patent:** **** Mar. 5, 2019**

(54) **AUDIO SPEAKER SYSTEM**

(71) Applicant: **Apple Inc.**, Cupertino, CA (US)

(72) Inventors: **Robert Brunner**, San Francisco, CA (US); **Eric Fields**, San Francisco, CA (US); **Xuan Shu**, San Francisco, CA (US)

(73) Assignee: **Apple Inc.**, Cupertino, CA (US)

(**) Term: **15 Years**

(21) Appl. No.: **29/562,521**

(22) Filed: **Apr. 26, 2016**

Related U.S. Application Data

(60) Continuation of application No. 29/493,898, filed on Jun. 13, 2014, now Pat. No. Des. 755,161, which is a division of application No. 29/458,750, filed on Jun. 21, 2013, now Pat. No. Des. 709,861, which is a division of application No. 29/410,580, filed on Jan. 9, 2012, now Pat. No. Des. 687,016.

(57) **CLAIM**

The ornamental design for an audio speaker system, as shown and described.

DESCRIPTION

FIG. 1 is a perspective view of an audio speaker system showing the claimed design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines in the figures show portions of the audio speaker system that form no part of the claimed design.

1 Claim, 6 Drawing Sheets
